APPARATUS FOR INTERNAL TRUING
OF HOLES

Robert Langel, Courteulary, Switzerland

Application October 25, 1947, Serial No. 782,116
In Switzerland August 8, 1941Section 1, Public Law 690, August 8, 1946
Patent expires August 8, 1961

7 Claims. (Cl. 51—59)

1

The present invention relates to apparatus and more particularly to apparatus for use in internal truing of holes which have been previously bored into a work piece.

According to an important feature of the invention, the apparatus comprises a block made of two parts within one of which there is arranged a plunger lodged in a bushing, this plunger being provided with a recess for use as an oil chamber adapted for lubrication of the truing tools and of the frictionally engaging surfaces of the movable parts of the apparatus, and means being provided for delivering oil into the said chamber and feeding it from this chamber to the said tools and movable parts.

Such an improved apparatus may be useful for instance in internal truing of holes which have been previously bored in watch plates or bridges, or in pieces of electric apparatuses or the like, and in a general way in pieces which are intended to be interchangeable.

The accompanying drawings represent, by way of examples, two practical embodiments of the invention. In the drawings:

Fig. 1 is a vertical sectional view of a first apparatus embodying the invention;

Fig. 2 shows a horizontal cross-sectional view thereof along the line *a*—*b* of Fig. 1;

Fig. 3 is a vertical sectional view of a second apparatus embodying the invention, and

Fig. 4 shows a horizontal cross-sectional view taken along the line *c*—*d* of Fig. 3.

The apparatus for internal truing of holes shown in the Figures 1 and 2 comprises a block made of two distinct parts, namely: a stationary lower block part 1 and a movable upper block part 2, both parts being connected with one another by means of two guiding posts 3 and 4 the lower ends of which are secured in vertical holes provided in the body of the stationary lower block part 1. This stationary lower block part 1 is secured to the table of a press (not shown) and the movable upper block part 2 is slidably mounted on the guiding posts 3 and 4 and is dependent upon the reciprocating movements of the said press. A plunger 5 is arranged within the stationary lower block part 1 and secured by its base to said block part by means of screws 6. The plunger 5 is axially bored through its whole length and carries on its upper part a tool supporting plate 7 covering the upper end of the plunger bore and to which is fastened a tool holding plate 8 adapted to hold the truing tools 9 in correct working position. The plates 7 and 8 are secured to the plunger 5 by means of screws 10. 55

2

The plunger 5 is lodged in and in sliding engagement with a bushing 11 which in turn is slidably mounted within a cylindrical recess provided in the lower block part 1, between the wall 5 of this recess and the body of the plunger 5. This bushing 11 carries at its upper extremity a plate 12 carrying in turn a second plate 13; both these plates are secured to the bushing 11 by means of screws 14 and constitute the bottom wall of this bushing.

In order to lubricate the above described plunger and bushing assembly as well as the tools held by the plates 7 and 8, the post 4 is provided with an axial channel 15 for the supply of the lubricating oil. From this channel 15, the oil is fed through a duct 16 and underneath the edge of the bushing 11 when the latter is in its upper position, as shown in Fig. 1. The oil is then delivered into the axial bore 17 of the plunger 5 intended as an oil chamber through inlet holes 18 provided in the lower part of plunger body. Two guiding pins 19 are intended to prevent rotation of the bushing 11 with respect to the plunger 5. From the oil chamber 17, the oil is then fed through holes 20 provided in the plates 7 and 8 into a hollow space 21 situated between the plates 8 and 12 to be further delivered to the tools and to the frictionally engaging surfaces of the plunger and of the bushing, when a pressure is exerted upon the bushing 11, by the work piece (not shown) which is suitably positioned and removably fastened to the bolster 60 of the movable upper block part 2.

In order to enable checking of the oil level in the channel 15, this channel is provided with a float F as shown in the Fig. 1.

The apparatus which is shown in Figures 3 and 4 comprises also a block made of two distinct parts 101 and 102, but the plunger 105 and the corresponding bushing 111 are lodged in a recess provided in the movable upper part 102 of the block. The upper block part 102 is slidably mounted on two posts 103 and 104 extending vertically from the lower block part 101 to which they are secured. The plunger 105 is provided with an oil chamber 117 and is secured by means of screws 22 to the movable upper part of the block. In the bushing 111 there are fixed screws 23 having a portion of their shank without threads and passing through holes provided in a flange of the plunger 105. These screws 23 are intended to limit the vertical movements of the bushing 111 with respect to the plunger 105, while preventing angular displacement of the bushing 50 with respect to the plunger. The bottom wall of

the bushing 111 is constituted by a single plate 24 secured to the cylindrical body of the bushing by means of screws 114. Reference numeral 160 designates the bolster of the stationary block part 101 on which the work piece (not shown) should be suitably positioned and secured for the truing of holes which have been previously bored thereinto.

In order to supply oil to the plunger 105, to the bushing 111 and to the tools 9, a channel 27 is provided in the body of the movable upper block part 102. This channel merges above a three-armed cross-bar 25 which is provided with a central aperture 28 for enabling oil to be fed into the oil chamber 117. A certain amount of oil passes also through the free space situated about the periphery of the cross-bar 25 to be supplied to the frictionally engaging surfaces of the bushing and of the plunger.

The operation of the apparatus for internal truing of holes which has been just described in connection with Figures 1 and 2 of the drawings is as follows:

When the movable part of the block carrying the work secured to the bolster 60 enters under actuation of the press in contact with the plate 13 of the bushing for truing holes previously bored in the work, the bushing is caused to slide downwardly on the plunger, thus pressing the oil which is comprised in the free space 21 situated between the plates 8 and 12 and urging it in part to the tools 9 and to the frictionally engaging surfaces of the bushing and of the plunger, whilst the remainder is delivered into the oil chamber 17. The truers 9 penetrate upwardly into the holes of the work and then into the corresponding holes of the bolster 60. The truing tools 9 suitably formed with slightly tapered free end portions, are well covered with oil and in penetrating the holes of the work true them thoroughly.

In order to draw the bushing 11 back into its initial position, there are provided pushers (not shown). The operation of the apparatus shown in Figures 3 and 4 only differs in that the truers penetrate downwardly into the holes of the work.

The apparatus for internal truing of holes as described and shown in the drawings is intended to avoid formation of scum; owing to the constant lubrication of the tools, the wear and tear of the latter will be practically reduced to zero. The tools will keep durably their cutting properties so that the waste of time for sharpening thereof will be reduced to a minimum extent. Owing to the cylindrical shape of the main pieces of the apparatus shown in the drawings the said pieces will be subjected neither to decentring nor to accidental displacements during the working.

What I claim is:

1. An apparatus for internal truing of holes which have been previously bored into a work piece, comprising in combination a block made of two distinct parts one of which is stationary and the other movable, a cylindrical recess in one of those distinct parts, a bushing slidably mounted in said cylindrical recess and having a bottom wall projecting from the outer surface of said recessed part facing the other block part, a plunger within said bushing in sliding engagement therewith and secured to said recessed block part, perforated plates holding said tool and secured to said plunger in spaced relation with said bottom wall of the bushing, said plates covering a recess in said plunger for use as an oil chamber for the oil destined to the lubrication of

said tool and of the frictionally engaging surfaces of said bushing and plunger assembly, and means for delivering oil into said chamber and into the space between said tool holding plates and said bottom wall of the bushing, whereby upon actuation of said movable block part, oil is circulated by pressure exerted thereon by said bushing.

2. An apparatus for internal truing of holes of the character described as claimed in claim 1, wherein the bushing and plunger assembly is mounted in the stationary part of the block.

3. An apparatus for internal truing of holes of the character described as claimed in claim 1, wherein the bushing and plunger assembly is mounted in the movable part of the block.

4. An apparatus for internal truing of holes of the character described comprising in combination a lower stationary block part having two cylindrical holes to receive two vertical guiding posts, a movable upper block part slidably mounted on said two vertical guiding posts, a cylindrical recess in said lower stationary part of the block to receive a bushing slidably mounted therein, said bushing having an outer bottom wall adapted to be pressed downwardly by said movable upper block part, a plunger within said bushing in sliding engagement therewith and secured by its base to said lower block part, said plunger being cylindrically bored and carrying tool holding plates covering the upper end of its bore and spaced apart from the bottom wall of said bushing at least one tool supported by said tool holding plates, an oil channel in at least one of said vertical guiding posts, said channel communicating underneath said bushing with holes in the wall of said plunger, and holes passing through said tool holding plates merging into the free space comprised between said plates and the bottom wall of said bushing, whereby oil may be fed upon actuation of said movable upper block part from said channel of the guiding post into said bore of the plunger and from said bore into said space between said tool holding plates and said bottom wall of the bushing for lubricating said tool and the frictionally engaging surfaces of said plunger and of said bushing.

5. An apparatus of the character described as claimed in claim 4, wherein the oil channel in the vertical guiding post is provided with a float for checking the level of the oil therein.

6. An apparatus of the character described as claimed in claim 4, wherein the bottom wall of the bushing is constituted by two superimposed plates having bores therein for guiding the tool held by the tool holding plates of the plunger.

7. An apparatus for internal truing of holes of the character described comprising in combination a lower stationary block part having two vertical guiding posts secured thereto, a movable upper block part slidably mounted on said vertical guiding posts, a cylindrical recess in said movable upper block part to receive a bushing slidably mounted therein, said bushing having an outer bottom wall adapted to be pressed upwardly by said stationary lower block part, a plunger within said bushing in sliding engagement therewith and secured by its base to said movable upper block part, said plunger being cylindrically bored and carrying tool holding plates covering the lower end of its bore and spaced apart from the bottom wall of said bushing at least one tool supported by said tool holding plates, a cross bar having a central aperture covering the upper end of plunger bore and secured to said plunger, an oil channel in the body of said movable upper

block part merging into said cylindrical recess thereof above said cross bar, and holes passing through said tool holding plates and merging into the free space comprised between said plates and the bottom wall of said bushing, whereby oil may be fed upon downward actuation of said movable upper block part from said channel into said bore of the plunger and from said bore into said space between said tool holding plates and said bottom wall of the bushing for lubricating said tool and the frictionally engaging surfaces of the plunger and of the bushing.
